UNITED STATES PATENT OFFICE

2,284,825

CIRCUIT INTERRUPTER

Oliver S. Jennings, Pittsburgh, and Harlan S. Gano, Wilkinsburg, Pa., assignors to Westinghouse Electric & Manufacturing Company, East Pittsburgh, Pa., a corporation of Pennsylvania

Application September 8, 1938, Serial No. 228,942

12 Claims. (Cl. 200—116)

The invention relates to electrical switches or circuit interrupters, in general, and more particularly to circuit interrupters of the type having an electro-responsive or thermal trip element for automatically causing operation of the interrupter in response to predetermined conditions.

Circuit interrupters having thermally responsive trip elements for tripping the interrupter in response to overloads of predetermined magnitude and duration may be materially affected by changes in ambient temperature. If the ambient temperature is higher than that for which the interrupter is calibrated, a part of the release movement of the thermal trip element occurs even before the overload arises, with the result that the interrupter is tripped open either at a lower current value or at a given current value in a shorter time. Conversely, if the ambient temperature is lower than that for which the interrupter has been calibrated, the required overload release travel of the thermal trip element is increased so that the interrupter will be tripped either at a higher current value or at a given current value only after a longer lapse of time. In some applications it is particularly important that the trip characteristic of the circuit interrupter remain unaffected by ambient temperature changes.

An object of the invention is the provision of a circuit interrupter, the trip characteristic of which remains substantially unaffected by changes in ambient temperature.

Another object of the invention is the provision of an electrical switch which will be automatically operated in response to definite predetermined overload conditions irrespective of any variations in ambient temperature.

Another object of the invention is the provision of a circuit interrupter embodying a thermal trip element and a means for compensating for changes in ambient temperature, the compensating means being so arranged that it is substantially unaffected by heat generated at the thermal trip element or within the circuit interrupter.

The novel features that are considered characteristic of the invention are set forth in particular in the appended claims. The invention itself, however, both as to structure and operation, together with additional objects and advantages thereof, will be best understood from the following detailed description of one embodiment thereof when read in conjunction with the accompanying drawing, in which:

Figure 1 is a vertical sectional view of a circuit breaker constructed in accordance with the invention;

Fig. 2 is an enlarged fragmentary sectional view showing the details of the thermal trip de-

vice and the means for compensating for changes in ambient temperature, the parts being shown in their normal positions;

Fig. 3 is a view similar to Fig. 2, showing the thermal trip element and the ambient temperature compensating means flexed in response to a rise in ambient temperature; and

Fig. 4 is a plan view of the trip device shown in Fig. 3.

Referring to the drawing, the circuit breaker comprises, in general, a base 7, a cover 9, contact means indicated generally at 11, an operating mechanism indicated generally at 13, and a trip device indicated generally at 15.

The base 7 is constructed of molded insulating material and forms a support for the various elements of the circuit breaker. The cover 9 which is also of molded insulating material, is secured to the base 7 by suitable means such as bolts (not shown), which pass through aligned openings formed in the base and cover. A pair of end terminals 19 are mounted in suitable openings provided in the ends of the base 7 and these terminals form the means for connecting the breaker in an electrical circuit.

The contact means indicated generally at 11 comprises a stationary contact 21 connected by a conductor strip 23 to one of the end terminals 19, a movable contact 25 carried by a resilient switch arm 27, and an arc-extinguishing means indicated generally at 29. The arc-extinguishing means is not an important part of the invention, and any suitable type may be used.

The movable contact 25 is secured to the free end of the resilient switch arm 27 by means of a rivet 30 and the opposite end of the switch arm 27 is secured to a channel-shaped movable contact supporting frame 31 by means of a pair of rivets 32. The channel-shaped contact supporting frame 31 is pivotally supported by means of a pivot pin 33 to the side walls of a metallic U-shaped main frame 35 secured to the base.

The operating mechanism 13 of the circuit breaker comprises, in general, a bifurcated operating member 37, a releasable member 39, a pair of toggle links 41 and 43, a pair of over-center springs 45 and an operating handle 47.

The operating member 37 has the lower ends of its legs pivotally supported on side walls of the main frame 35 by means of pivot studs 48. The upper end of the operating member 37 has secured thereto an arcuate closure member 49 of molded insulating material, which acts to close an opening 51 provided in the cover 9 in any position of the operating member 37. The handle 47 is formed integral with the closure member 49 and projects through the opening 51 in the cover 9. A resetting member 53 projects from and is formed integral with the operating member 37 and this member serves to reset the re-

leasable member 39 following a tripping operation, as will be described hereinafter.

The releasable member 39 is pivotally supported by means of a pivot pin 55 which extends between the side walls of the main frame 35. The releasable member has a rearwardly extending portion 57 provided with a latch 60 which is insulated from the releasable member 39 by a plurality of mica plates 62. The releasable member 39 is adapted to be normally held in latched position by means of the trip device 15.

The toggle links 41 and 43 pivotally connect the channel-shaped contact supporting frame 31 to the releasable member 39 in the manner shown in Fig. 1 of the drawing. The over-center springs 45 are connected between lugs 59 formed integral with the top of the operating member 37, and a knee pivot pin 61 which pivotally connects the toggle links together.

The operation of the circuit breaker as thus far described is briefly as follows. With the parts in the position shown in Fig. 1, that is, with the contact means in closed-circuit position and the releasable member 39 held in its normal latched position by the trip device 15, let it be assumed that it is desired to manually open the circuit controlled by the breaker. The operating handle 47 is moved from the closed position shown in Fig. 1 in a counter-clockwise direction to an open-circuit position at the opposite end of the opening 51. This movement of the operating handle 47 to open position moves the operating member 37 in a counter-clockwise direction about its pivot axis 48. At a certain point in the opening movement of the operating member 37, the over-center springs 45 change their line of action with respect to the pivot point 58 of the upper toggle link 41 and cause collapse of the toggle links 41 and 43. The collapse of the toggle links causes movement of the switch arm 27 in a counter-clockwise direction to open-circuit position with a snap action.

In manually closing the circuit breaker, substantially the reverse action takes place. The operating handle is returned to the closed position shown in Fig. 1. At a predetermined point in the closing movement of the operating handle 47, the over-center springs 45 change their line of action with respect to the pivot point 58 and cause the toggle links 41 and 43 to assume their extended or "in-toggle" position as shown in Fig. 1. Movement of the toggle links to their extended position causes clockwise movement of the movable contact supporting frame 31 and switch arm 27 to closed-circuit position with a snap action to effect engagement of the movable contact 25 with the stationary contact 21.

The releasable member 39 is always biased in a clockwise direction about its pivot axis 55 by a component of force exerted by the over-center springs 45, and the trip device 15 under normal conditions holds the releasable member in its normal latched position against the biasing action of the springs 45. If an overload of predetermined magnitude and duration occurs in the circuit controlled by the breaker, the trip device operates to effect release of the releasable member 39. The member 39 when released, is rotated in a clockwise direction about its pivot axis 55 by the springs 45 and at a predetermined point in its movement changes the line of action of the over-center springs 45 relative to the pivot pin 58 to cause collapse of the toggle links and resulting movement of the switch arm 27 to open-

circuit position with a snap action to interrupt the circuit controlled by the breaker.

After a tripping operation, the breaker cannot be reclosed without first moving the operating handle 47 to the full open-circuit position. The resetting movement of the operating handle 47 to the open-circuit position causes the resetting member 53 to engage and move the releasable member 39 in a counter-clockwise direction to the position shown in Fig. 1, in which it is relatched by the trip device 15.

The trip device comprises a thermally responsive trip element in the form of a bimetallic strip 63, which is pivotally mounted at its lower end on the base 7. The lower end of the bimetallic element is bent at a right angle and secured in any suitable manner to a U-shaped bracket 65. The bracket 65 is pivotally mounted on a U-shaped supporting bracket 67 by means of a pivot pin 69 which extends through the side legs of the brackets 65 and 67. The supporting bracket 67 is seated on the base 7 and is rigidly secured thereto by a pair of downwardly extending projections 71 which pass through openings in the base 7 and have their lower ends clinched over against a plate 73 engaging the underside of the base 7.

The upper end of the bimetal trip element 63 is provided with an adjustable latch element 75 in the form of an adjusting screw which is threaded through the free end of the trip element 63. The latch element 75 is normally adapted to overlap the latch 68 carried by the releasable member 39 to hold the releasable member 39 in its normal position shown in Fig. 1. The bimetallic trip element is connected in series circuit with the contacts 25 and 21 of the circuit breaker by means of a pair of flexible series conductors 77 and 79, so as to be responsive to the current flowing in the controlled circuit. The series conductor 77 has one end connected to the left-hand terminal 19 and its other end connected to the upper free end of the bimetallic trip element 63. The flexible series conductors 79 are secured to the bent foot of the bimetallic trip element 63 at one end and their other ends are secured to a terminal strip 81. The terminal strip 81 is secured to a horizontal extension of the mounting bracket 67 by means of a screw 83 (Fig. 4). The other end of the conducting strip 81 is connected by flexible series conductors 85 to the resilient switch arm 27.

The circuit through the breaker extends from the left-hand terminal 19 through the flexible conductor 77, bimetallic trip element 63, flexible conductors 79, conductor strip 81, flexible conductors 85, resilient switch arm 27 through the contacts 25 and 21 and the conducting strip 23 to the opposite terminal 19.

The bimetallic trip element 63 is normally held against rotation about its pivot axis 68 in the position shown in Fig. 1, by means which will be hereinafter described. When an overload of predetermined magnitude and duration occurs in the circuit controlled by the breaker, the bimetallic trip element 63 is heated by the overload current and flexes in a direction away from the operating mechanism 13 to cause the latch element 75 to release the releasable member 39. The release of the member 39 effects opening of the circuit breaker in the manner previously described. After the circuit has been interrupted, the bimetallic trip element 63 cools and returns to its normal position shown in Fig. 1, to permit resetting of the circuit breaker.

The circuit breaker is calibrated at the factory by means of the adjustable latch element 75 so that it will trip open in response to overload currents of definite predetermined magnitude and duration. After the breaker has been calibrated, the adjusting screw 91 is sealed by a suitable sealing material to maintain the calibration permanent.

As has previously been pointed out, the bimetallic trip element 63 is affected by changes in ambient temperature. If the ambient temperature rises, the bimetallic trip element 63 deflects in a direction away from the operating mechanism an amount proportional to the rise in ambient temperature. This decreases the amount of latch overlap between the latch element 75 and the latch 60, with the result that the breaker will be tripped open either at a lower current than that for which it was calibrated, or at a given overload current in a shorter period of time. Conversely, if the ambient temperature decreases, the bimetallic trip element 63 will deflect in a direction toward the mechanism 13 and tend to increase the amount of latch between the elements 75 and 60, with the result that the breaker will be tripped open either at a higher current value than that for which it was calibrated, or at a given overload current after a longer period of time.

In order to prevent changes in ambient temperature from affecting the trip characteristic of the trip element 63, and to insure that the breaker will be tripped open in response to definite predetermined overload conditions, irrespective of changes in ambient temperature, there is provided an ambient temperature compensating means comprising a bimetallic strip 87. The strip 87 is secured at one end by means of a rivet 89 in a recess provided on the underside of the base 7. The free end of the bimetallic strip 87 is connected to the bracket 65, which carries the trip element 63, through the agency of an adjusting screw 91 and an insulator 93. The insulator 93 extends through a small opening in the base and is provided with a slot 95 adjacent its upper end, which is engaged in a slot 97 formed in an extension 99 of the bracket 65. A suitable spring, not shown, may be provided for biasing the bimetallic trip element in a clockwise direction about its pivot axis 69 to maintain the legs 101 of the bracket 65 in engagement with the lower edges of the slot 95 in the insulator 93.

The operation of the ambient temperature compensating means is briefly as follows. If the ambient temperature rises, the bimetallic trip element 63 is deflected toward the left away from the operating mechanism 13. However, the bimetallic strip 87 is arranged so that it deflects downwardly to cause the bracket 65 and the bimetallic trip element 63 to partially rotate in a clockwise direction to compensate for the ambient temperature deflection of the bimetallic trip element 63. This position of the parts is illustrated in Fig. 3. Conversely, if the ambient temperature decreases, the bimetallic trip element 63 deflects toward the operating mechanism 13. At the same time, however, the bimetallic strip 87 is deflected upwardly by the decrease in ambient temperature to rotate the bimetallic trip element 63 in a counter-clockwise direction to compensate for the ambient temperature deflection thereof. It will thus be seen that the bimetallic strip 87 always maintains the same amount of overlap between the latch 75

element 75 and the latch 60 irrespective of any change in ambient temperature, so that the breaker will always be tripped open in response to definite predetermined overloads, irrespective of any changes in ambient temperature.

The mounting arrangement of the bimetallic strip 87 on the underside of the base and away from the bimetallic trip element 63 and the insulating connection 93 is an important feature of the invention since with this mounting arrangement and connection, the base 7 and the insulator 93 substantially completely heat insulate the bimetallic strip 87 from the bimetallic trip element 63 and the other conducting parts of the circuit breaker. Thus heat generated at the bimetallic trip element 63 or internally within the circuit breaker is prevented from affecting the bimetallic strip 87.

The adjusting screw 91 is accessible from outside of the circuit breaker casing and serves to adjust the trip characteristic of the bimetallic trip element 63. Turning the screw 91 in or out changes the amount of overlap between the latch element 75 and the latch 60.

By varying the deflection characteristics of the bimetallic strips 63 and 87 with respect to each other, the bimetallic trip element 63 may be under, fully, or over-compensated for changes in the ambient temperature, or arranged to give any other desired characteristic of compensation.

While the invention has been disclosed in accordance with the provisions of the patent statutes, it is to be understood that various changes in the structural details thereof may be made without departing from the spirit of the invention. It is desired, therefore, that the appended claims be given the broadest reasonable interpretation permissible in the light of the prior art.

We claim as our invention:

1. In a circuit interrupter, relatively movable contacts for opening and closing the circuit, actuating means for opening and closing said contacts, means including a bodily movable thermal control element heated in response to the current in the circuit and movable in response to predetermined overload conditions in the circuit to effect actuation of said contacts, and a thermally responsive member having one portion rigidly secured to a fixed support and having a free portion connected to said control element to bodily displace said control element in compensating for changes in ambient temperature.
2. In a circuit interrupter, a pair of relatively movable contacts for opening and closing the circuit, a bodily movable electro-responsive control element heated in response to the current in the circuit and movable a predetermined amount in response to predetermined current conditions to effect actuation of said contacts, and a bimetallic member rigidly mounted at one end on a fixed support and having its free end connected to said control element by an adjustable heat insulating connecting means for bodily displacing said control element in response to changes in ambient temperature.
3. In a circuit interrupter, relatively movable contacts for opening and closing the circuit, actuating means for opening and closing said contacts, means including a pivotally mounted bimetallic trip element heated in response to the current in the circuit and movable in response

to predetermined overload conditions to cause opening of said contacts, and a bimetallic member having one end rigidly mounted on a fixed support and its free end connected to said trip element for compensating for changes in ambient temperature.

4. In a circuit interrupter, a casing, a switch member mounted in said casing for movement to open and to closed circuit position, operating means for moving said switch member to closed circuit position, means including a thermal control element mounted in said casing, heated by the current in the circuit and movable when heated a predetermined amount by the passage of overload currents of predetermined magnitude and duration to cause movement of said switch member to open circuit position irrespective of the position of said operating means, and a thermally responsive member mounted on the outside of said casing and connected to said thermal control element for compensating for changes in ambient temperature.

5. In a circuit interrupter, a casing, relatively movable contacts mounted in said casing, a bimetallic trip element movably mounted in said casing and heated in response to the current flowing in the circuit, said trip element being adapted to flex a predetermined amount in response to predetermined overload conditions to cause opening of said contacts, and a thermally responsive member mounted on the outside of said casing and connected to said trip element for compensating for predetermined changes in temperature.

6. In a circuit interrupter, relatively movable contact members for opening and closing the circuit, operating means including a manually operable means for opening and closing said contact members, a bodily movable bimetallic control element heated by the current in the circuit and operable when heated in response to predetermined current conditions to flex a predetermined amount and cause actuation of said contact members, a thermally responsive member connected to said control element to bodily move said control element in compensating for changes in temperature, and means for substantially preventing heat generated at said control element and in said interrupter from affecting said thermally responsive member.

7. In a circuit interrupter, relatively movable contacts for opening and closing the circuit, actuating means for opening and closing said contacts, means including a bodily movable bimetallic trip element heated in response to the current flow in the circuit, said trip element being adapted to flex a predetermined amount in response to predetermined overload conditions to cause opening of said contacts, a bimetallic member rigidly mounted at one end on a fixed support, and an adjustable heat insulating connection between the free end of said bimetallic member and said trip element, said bimetallic member being operable to compensate for changes in the temperature surrounding said member.

8. In a circuit interrupter, relatively movable contacts, actuating means for opening and closing said contacts, a spring biased member releasable to cause opening of said contacts, a pivotally mounted bimetallic trip element heated in response to the current flow in the circuit, said trip element being adapted to flex in response to predetermined overload conditions to effect re-

lease of said member and opening of said contacts, a casing for enclosing said elements, and a bimetallic member rigidly mounted at one end on the exterior of said casing and having its free end connected to said trip element for compensating for changes in the surrounding temperature.

9. In a circuit interrupter, a casing, relatively movable contacts mounted in said casing, a bimetallic trip element pivotally mounted in said casing, heated in response to the current flow in the circuit, said trip element being adapted to flex in response to predetermined overload conditions to cause opening of said contacts, a bimetallic member rigidly secured at one end on the exterior of said casing, and means including an adjusting screw connecting the free end of said bimetallic member to said trip element, said bimetallic member being operable to compensate for changes in ambient temperature, said adjusting screw being accessible from outside said casing.

10. A circuit controlling means comprising a base, a bimetallic control element bodily movable on said base and heated in response to the current flow in the controlled circuit, said element being adapted to be flexed in response to predetermined overload conditions and also flexed in response to changes in ambient temperature, a thermally responsive member rigidly secured at one end to said base on the opposite side thereof from said control element and having its free end connected to said control element to compensate for ambient temperature movement of said control element.

11. In a circuit interrupter, relatively movable contacts, actuating means for opening and closing said contacts, said actuating means including a member releasable to cause automatic opening of said contacts, means for latching said member comprising a pivotally mounted bimetallic trip element heated in response to the current of the circuit, said trip element being adapted to flex when heated a predetermined amount in response to overload currents to cause said latching means to release said releasable member, a second bimetal element rigidly mounted at one end on a fixed support and having its free end connected to said pivotally mounted bimetallic trip element by means including an adjusting screw, said second bimetal element serving to compensate said pivoted bimetallic trip element for changes in ambient temperature, and said adjusting screw being adjustable to vary the amount of latch overlap to thereby adjust the trip characteristic of the breaker.

12. In a circuit interrupter, a casing, relatively movable contacts in said casing, actuating means for opening and closing said contacts, a pivotally mounted bimetallic trip element in said casing heated in response to the current of the circuit, said trip element being adapted to flex when heated a predetermined amount in response to overload currents to cause said actuating means to open said contacts, a second bimetallic element rigidly mounted at one end on a fixed support and having its free end connected to said pivoted bimetallic element to compensate for changes in ambient temperature, said second bimetallic element being substantially isolated from heat radiation and convection currents from said bimetallic trip element and exposed to the temperature of the medium outside of the casing.
